UNITED STATES PATENT OFFICE.

JEROME SULZBACHER, OF NEW YORK, N. Y.

ALARM-CABLE.

1,109,878.

Specification of Letters Patent.

Patented Sept. 8, 1914.

Application filed December 30, 1911. Serial No. 668,649.

To all whom it may concern:

Be it known that I, JEROME SULZBACHER, a citizen of the United States, and a resident of the city, county, and State of New York, (whose post-office address is No. 1 West Eighty-fifth street, New York city, New York,) have invented certain new and useful Improvements in Alarm-Cables, of which the following is a specification.

10 My invention relates to that class of cables which are intended to give an automatic alarm in the event of fire, attempted burglary, or other happenings which are of a nature to make it advisable to attract the 15 attention of those guarding the property intended to be protected by said cable, and are so arranged that the cutting or other interruptions of the circuit, as by the opening of a window or door will give an alarm, commonly known as a burglar alarm.

20 The object of my invention is to construct such a cable in a novel, effective, and substantial way which shall be unusually quick, certain and more specifically definite in its 25 action and which shall have the added feature of being used as a conduit for such wiring as may be desired for electric lights, telephones, bells or other devices in the premises to be protected by the alarm cable.

30 My cable is therefore preferably constructed with a hollow center to serve as said conduit and broadly speaking my invention consists in so arranging what may be called the burglar wires that they are less accessible 35 to the attack of cutting implements and so arranging the thermostatic element as to be sufficiently exposed to allow quick access to the flame or heated air of an incipient fire.

40 Where a continuous thermostatic element is employed in alarm cables and where the same wire gives an alarm from all interruptions in the circuit, it is often difficult to determine with necessary quickness the exact 45 location of the trouble. My improved cable is to be so constructed that the alarm given, whether delivered at a single point, or at many places as desired, always locates itself so that attention is directed to the exact spot 50 where the trouble occurs. To this end instead of a continuous thermostatic element which by fusing, always short circuits the same two wires, I employ a number of thermostatic sections arranged at intervals along 55 a cable consisting of many different wires so that each point at which the fire is liable

to occur has its corresponding thermostatic section and each section acts upon a different circuit wire so that when an alarm is received at the various signal stations, it can only have come from the particular section which has given the alarm. With the burglar alarm it is not of so much importance, but wherever it is important, the same system of section signaling can be employed. 60 65

In the accompanying drawing, I have shown a very simple form of my improved alarm cable, showing four sections; it being understood that the number of sections corresponds to the number of rooms in the 70 building or the number of separate buildings which may be included in the same alarm circuit.

Figure 1 is a side elevation broken away to show various portions. Fig. 2 is a cross 75 section on line 2—2 of Fig. 1.

Same letters indicate similar parts in the different drawings.

A is a tube of any suitable material preferably of insulating material adapted to 80 serve as a conduit in which one or more wires may be carried for the purpose of running electric lights, telephones, door bells or other bells and for such other wires as are commonly used for household or office 85 purposes. Around this conduit is wound the alarm portion of my improved cable, designated as B, and which consists of any desired number of separate independent insulated signal wires *a*, *a*, and a general circuit or current wire *b*, (see Fig. 2). These various wires are preferably braided to form a net work of considerable resistance to any attempt to cut the same as shown in Fig. 1 and may also be embedded in a fabric of 90 95 insulating material *c*, although this latter is not necessary.

C C represent a plurality of thermostatic surfaces which are shown as arranged along the cable at intervals. The dimensions and 100 character of these thermostatic portions will naturally vary with the space which they are to protect; the theory of my alarm cable being that each thermostatic section or portion should be of sufficient extent and character to afford substantial protection to the locality in which it is used, while the cable between protected stations needs no thermostatic covering. For example: where my improved alarm cable is to be used for the 105 protection of various rooms in the same building, the thermostatic portion in each 110

room should present a sufficient exposure to act quickly in response to any fire which starts in any part of said room, while that portion of the cable which passes through 5 walls or floors needs no thermostatic protection being so located that fire could hardly attack it unless well advanced.

Where my alarm cable is to be used to protect various floors or apartments in the 10 same building the thermostatic portions will be located with regard to the portions most liable to fire in each apartment or floor, as for instance near the heat apparatus, lighting apparatus, electric wiring, or especially 15 combustible articles. For the same reason in stores the cable would preferably run along the counters and shelves as also any place where paper or other waste is likely to be thrown.

20 Where my improved cable is to be used for the protection of several buildings placed in the same circuit as for instance factories, farm buildings, store houses etc., the same theory of exposure and protection 25 applies on a larger scale. It will thus be seen that the number of thermostatic portions will correspond practically to the number of places which have to be identified and located by means of the alarm cable

30 and consequently the number of independent alarm wires constituting the main body of the cable will correspond in number with said thermostatic sections. Each thermostatic section is to be so located on the cable 35 that, when it acts under the influence of excess heat, whether caused by flame or by other undue elevation of the temperature beyond the fixed limits, it will fuse or expand or otherwise respond to this excess 40 heat so as to bring about an electric connection between the cable signal wire corresponding to said section and the circuit wire of the cable so that an alarm whether visible or aural will be given, at such station 45 or stations as may be selected for that purpose and placed within the general alarm circuit. Where the number of protected places and thermostatic portions is small, a single circuit wire may be sufficient, but 50 where their number is very large, a plurality of return wires is preferable.

It will be readily understood that the advantages of my improved alarm cable consist primarily in having the thermostatic 55 portions most readily accessible and therefore most certain to respond in case of need, while the burglar portion is least accessible to attack. While I have shown my im-

proved cable in this simple and somewhat skeleton form, it will be readily understood 60 that coverings of a protective or insulating character may be employed according to choice, provided such extra coverings do not interfere with the proper and quick responsive action of the thermostatic portions 65 of the cable.

By the above statement that the thermostatic section will fuse or expand or otherwise will respond to excess heat so as to bring about an electric connection between 70 its corresponding signal wire, and the circuit wire of the cable, I mean simply to call attention to the well known fact that some thermostats bring about the necessary electrical connection by fusion, some by expansion, 75 and some by other well known methods. I am not to be understood as saying that my thermostatic section is wholly composed of fusible material in any case, nor do I claim any novelty in the method of bringing about 80 the desired electric connection. The purpose of my invention is to provide an alarm cable of such construction that each protected station sends an independent and distinguishable signal instead of a mere general alarm as heretofore.

I claim:

1. An alarm cable which comprises a number of signal wires and a circuit wire held together by suitable coverings to form the 90 main body of the cable and a number of independent thermostatic sections arranged at intervals on the outside of said main body and each adapted to bring about an electric connection between its corresponding signal 95 wire and the circuit wire in response to excess heat; whereby each thermostatic section gives a different alarm from every other thermostatic section.

2. An alarm cable which comprises a hollow tube adapted to serve as a conduit, a number of signal wires, and a circuit wire held together by suitable coverings to form the main body of the cable and a number of independent thermostatic sections arranged at intervals on the outside of said main body and each adapted to bring about an electric connection between its corresponding signal wire and the circuit wire in response to excess heat; whereby each thermostatic section gives a different alarm from every other thermostatic section.

JEROME SULZBACHER.
